UNITED STATES PATENT OFFICE.

HARRY E. DOERR, OF ST. LOUIS, MISSOURI.

BRAKE-BEAM HANGER.

1,257,590.

Specification of Letters Patent. Patented Feb. 26, 1918.

Application filed November 12, 1915. Serial No. 61,119.

To all whom it may concern:

Be it known that I, HARRY E. DOERR, a citizen of the United States, residing in the city of St. Louis and State of Missouri, have 5 invented certain new and useful Improvements in Brake-Beam Hangers, of which the following is a specification.

This invention relates to brake beam hangers for railway cars, and its purpose is to 10 provide improved means for supporting the usual brake beam from the car truck.

The principal object of the invention is to provide an improved brake hanger construction which will permit the desired 15 movement of the brake beam with respect to the wheels of the truck, while at the same time positively preventing the accidental or unintentional detachment or disengagement of the brake beam, and parts carried thereby, 20 when the brake beam is in its normal operative position. A further object is to provide a brake hanger which may be detached so as to release the brake beam only when the hanger is displaced from its normal operative 25 position, which displacement is normally prevented by parts of the car truck. Still another object is to provide an improved form of bracket or lug for supporting the hanger, and improved means for 30 connecting the hanger to the bracket. This connecting means positively prevents the detachment of the hanger from the bracket when the brake beam is in its normal operative 35 position, and by this means the accidents which follow the dropping or displacement of the brake beam are avoided. A further object relates to the means which are provided for permitting the ready removal of the hanger from the bracket, when desired. 40 These and other objects of the invention will be more specifically set forth in connection with the following specification, taken in connection with the accompanying drawings, in which several embodiments of the 45 invention are illustrated.

In the drawings—

Figure 1 is a side elevation of the side frame of a car truck, showing various parts associated therewith in section, and showing 50 the preferred form of my improved brake hanger in elevation.

Fig. 2 is a sectional view, taken on the line 2—2 of Fig. 1.

Fig. 3 is a perspective view of the connecting pin used with the form of the invention 55 shown in Figs. 1 and 2.

Fig. 4 shows a side elevation of a modified form of hanger.

Fig. 5 is a perspective view of a connecting pin for use in connection with the form 60 of the invention shown in Fig. 4.

Fig. 6 is a perspective view of the upper portion of the hanger shown in Fig. 4.

Fig. 7 is an end elevation of still another modification of my invention.

Fig. 8 is a partial elevation of the reverse side of the structure shown in Fig. 7.

Fig. 9 is a sectional view, taken on the line 9—9 of Fig. 7.

Fig. 10 is a sectional view through the side frame, showing a side elevation of the bracket or lug used in connection with still another modification of my invention.

Fig. 11 is a sectional view, taken on the line 11—11 of Fig. 10.

Fig. 12 is a perspective view of the upper portion of the hanger used in connection with the structure shown in Figs. 10 and 11.

Fig. 13 is a view similar to Fig. 1, showing a still further modification of the invention.

Fig. 14 is a sectional view, taken on the line 14—14 of Fig. 13; and

Fig. 15 is a perspective view of the connecting pin used in connection with the form of the invention illustrated in Figs. 13 85 and 14.

In the drawings I have illustrated my invention in connection with a well-known form of car truck having the side frame 20, comprising the upper arch bar 20^a, lower arch bar 20^b, and side columns 20^c. The truck bolster 21 has the end portion thereof mounted between the side columns of the side frame, and the lower arch bar supports the spring plank 22. The brake beam 23, of channel form, has mounted thereon and secured thereto the brake head 24, which has fixed therein a brake shoe 25 adapted to coast with the periphery of the car wheel 26, shown by dotted lines.

Extending inwardly from the side frame, transversely to the plane thereof from a point preferably adjacent the junction of the side column 20^c and upper arch bar 20^a, is the bracket or lug 28, which is preferably formed integrally with the side frame. This bracket comprises a flange or plate 28^a, which is preferably inclined upwardly from the horizontal toward the adjacent end of the side frame, and formed integrally with this plate or flange is the upwardly extending rib 28^b connecting the plate 28^a with the

upper arch bar 20^a. A depending arm or hub 29 is formed integrally with the under side of the plate 28^a at the outer end thereof, and this hub is provided with an aperture 30 extending parallel to the axis of the wheel 26. The aperture 30 is adapted to receive the connecting pin 31 which forms a bearing for the brake hanger 32. The brake hanger in this form of the invention is substantially 10 U-shaped, comprising two parallel arms 32^a and a transverse member 32^b which is adapted to extend through the aperture 24^a in the brake head and form a bearing therefor. Each of the arms of the hanger are provided 15 with enlarged upper extremities 32^c, which are provided with apertures 32^d adapted to receive and be journaled on the projecting extremities of the connecting pin 31.

The connecting pin has formed integrally therewith a central elongated lug 31^a and two end lugs 31^b, all of said lugs being of substantially U-shape in cross section, and being arranged in alignment with each other projecting transversely to the axis of the pin.

20 The depending hub 29 of the bracket is provided with a transverse slot or notch 29^a, which communicates with the aperture 30, preferably on the upper side thereof, substantially in the same plane as the rib 28^a.

25 The enlarged extremities 32^c of the hanger 32 are similarly provided with transverse slots or notches 32^e, which communicate with the apertures 32^d, preferably in a plane lying transversely to the plane of the arms 32^a.

30 The slots or notches 29^a and 32^e are of similar size, and of substantially the same contour as the lugs 31^a and 31^b projecting from the connecting pin, so that when the hanger is placed in the position illustrated by dotted lines 32^f in Fig. 1, the notch 32^e will align with the notch 29^a, so that the connecting pin may be passed into or removed from the alining apertures 30 and 32^d, during which operation the projecting lugs 31^a and 31^b will

40 pass through the alining notches 29^a and 32^e. The elongated lug 31^a has a length substantially equal to the length of the hub portion 29 of the bracket, and the spaces between the lugs 31^a and the lug 31^b are of such size as to receive and be somewhat closely fitted by the enlarged hub portions 32^c of the hanger. When the hanger is in the position illustrated by dotted lines 32^f in Fig. 1, and the pin 31 has been inserted to such position

45 that the spaces between the lugs 31^a and 31^b register with the hub portions 32^c of the hanger, the hanger may be lowered to the position shown in Fig. 1, for instance, when the notches 32^e will pass out of registry with the lugs 31^b, whereby the hanger will be retained in pivotal connection with the bracket. The lug 31^a will then be seated in the notch or slot 29^a, so that the pin will be maintained in non-rotative engagement with the bracket,

50 but the hanger will have a rotative engage-

ment with the pin 31, and will be permitted to move angularly in its normal position through a space determined by the usual working limits of the brake and brake beam. It will be observed that a considerable angular movement of the hanger from the normal position shown in Fig. 1 is necessary to bring the notches 32^e and 29^a in registry, so as to permit the removal of the pin. In this construction the slots 32^e are directed 70 toward the end of the side frame and toward the wheel 26, so that after the wheel and the axle upon which it is mounted have been assembled on the truck, the wheel will prevent the brake shoe and brake beam from 80 being moved to such position as to permit removal of the pin and detachment of the hanger. It will be observed that the spring plank 22, carried by the side frame, and also the truck bolster, will prevent angular movement of the brake hanger in the other direction, so as to bring the notches or slots 29^a and 32^e into alignment.

55 In the form of the invention illustrated in Figs. 4, 5, and 6 the hanger bracket 35 is of substantially the same form as the bracket 28 previously described, except that the depending hub portion 36 thereof is provided with a vertically extending slot 36^a, which is adapted to receive the head 37^a of the hanger 37, which, in this construction, is in the form of a loop having a transverse arm 37^b adapted to form a bearing for the brake head, by means of which the brake beam is carried. The head 37^a of the hanger 37 is provided 90 with a circular aperture 37^c, having a U-shaped slot 37^d communicating therewith in a plane transverse to the plane of the hanger. When the head 37^a is placed in the slot 36^a of the head 36, the aperture 37^c and slot 37^d 100 are adapted to register with the similar apertures and notches 36^b formed through the oppositely disposed portions of the head 36 parallel to the longitudinal axis of the bracket 35. A cylindrical connecting pin 38 105 is then adapted to be passed through the alining apertures and notches of the bracket and hanger, this pin being provided with transversely projecting U-shaped lugs 38^a, which are spaced apart a distance substantially equal to the width of the slot 36^a, so that when the pin is passed into position the central portion thereof will form a bearing for the head 37^a of the hanger, and the lugs 38 will engage the corresponding notches in 11 the hub 36, so as to fix the pin in non-rotative engagement with respect to the bracket. It will, of course, be understood that with this form of the invention, also, the notches or slots in the head 36 are arranged to be out of alignment with the notch 37^d when the hanger is in its normal operative position.

110 In the third form of the invention shown in Figs. 7, 8, and 9, the upper arch bar 10^a 1

of the side frame has formed integrally therewith and projecting transversely to the plane thereof, a substantially cylindrical lug or hanger bracket 40, having a circular bore 41 formed therethrough, which is adapted to receive and closely fit the inner cylindrical portion 42^a of the pin 42. This pin is provided with an enlarged annular shoulder 42^b, which seats against the extremity of the bracket 40, and the end of the portion 42^a opposite the annular shoulder 42^b is adapted to be riveted into a rectangular recess 43, which is formed in the arch bar 10^a in communication with the bore 41. The hanger 44, used in connection with this form of the invention, is in all respects similar to that shown in Figs. 4 and 6, being provided with an aperture 44^a having a notch or slot 44^b communicating therewith transversely to the plane of the hanger. The pin 42, projecting outwardly from the annular shoulder 42^b, is adapted to engage the aperture 44^a and form a bearing for the hanger, the pin being provided at its extremity with an upwardly projecting U-shaped lug 42^c, which is adapted to register with the notch or slot 44^b when the hanger is moved upwardly to the required extent from the normal operative position shown in Fig. 7. It will be seen that since the extremity of the pin is riveted into the rectangular aperture 43, said pin will be maintained in non-rotative engagement with the bracket, so that the pin will be prevented from moving to such position as to cause an accidental registry of the lug 42^c with the notch 44^b.

In the fourth form of the invention illustrated in Figs. 10, 11, and 12, the hanger bracket 45, which is preferably formed integrally with the side frame, comprises the reinforcing rim 45^a, the substantially horizontal flange 45^b, and the substantially vertical flange 45^c. Formed integrally with the upright flange 45^c and the overhanging flange 45^b, are two substantially parallel flanges 46. A cylindrical bearing 47 is formed within these flanges, and the hanger 48, of substantially the same form as those shown in Figs. 4 and 9, has formed integrally with the rectangular stem 48^a thereof, a connecting pin 49, which is adapted to be journaled in said bearing. The pin is provided with oppositely disposed flattened surfaces 49^a, and the stem 48^a is adapted to enter the notch 50 formed between the flanges 46. The flanges 46 are provided on opposite sides of the notch or slot 50 with oppositely disposed guide-ways 51, which are of substantially the same width as the distance between the flattened faces 49^a of the pin, so that when the hanger is turned upwardly into a position substantially in alignment with the notches 51, the pin may be inserted in or withdrawn from the bearing 47, but when the hanger is turned downwardly to normal or operative position, the removal of the pin from its bearing will be prevented, owing to the fact that the pin 49 has a diameter greater than the width of the slots 51.

In the fifth form of my invention shown in Figs. 13, 14, and 15, the bracket 55 comprises a reinforcing rib 55^a, a horizontal flange 55^b, and a substantially vertical flange 55^c, all of these flanges being preferably formed integrally with each other and with the side frame 10. The flanges 55^b and 55^c of the bracket are formed integrally with the parallel vertically extending flanges 55^d, which are provided with alining circular apertures 56 extending parallel to the axis of the wheel 26. The flanges 55^d are further provided with alining notches or slots 56^a which communicate with the apertures 56, preferably on the lower side thereof and toward the central portion of the side frame. The hanger 57 is provided with a head 57^a, which is adapted to extend upwardly between the flanges 55^d, and which is apertured to be engaged by the connecting pin 58. The aperture in the hanger has a notch or slot 57^b communicating therewith, substantially in the plane of the hanger, and when the hanger is moved to the dotted position indicated by the numeral 59 in Fig. 13, the notch 57^b will register with the notches 56^a, so as to permit the insertion or withdrawal of the pin 58, which has formed integrally therewith a projecting lug 58^a of substantially the same form and contour as the notches 56^a and 57^b. When the pin has been passed into engaging position, as shown more clearly in Fig. 14, the hanger may be passed from the position shown by dotted lines in Fig. 13, to the normal or operative position shown by full lines, and when this is done the lug 58^a will be passed out of alinement with the notches 56^a so as to prevent removal of the pin. It will be apparent that in this form of the invention the pin is fixed in non-rotative engagement with respect to the hanger, and that it rotates with respect to the bracket. It will also be apparent that with the form of construction shown, the brake beam and brake carried thereby will normally be prevented from moving to detaching position, corresponding to the position illustrated by dotted lines 59 in Fig. 13 by the spring plank carried on the lower arch bar of the side frame.

In all of the forms of my invention above described, it will be seen that after the hanger has been adjusted and the parts of the truck assembled, the removal of the connecting pin, and the corresponding removal or displacement of the brake beam, is prevented by the car wheels and spring plank, as well as by other parts of the car structure, but in all of the forms described the

hanger is permitted to move angularly through the required working limits, which I term its normal operative position, without danger of displacement of any of the parts. These various forms of the invention have the advantage that they permit ready detachment or displacement of the hanger and brake beam when desired, while positively preventing accidental displacement during the operation and movement of the car.

Although I have shown various different forms of the invention in order to make clear to those skilled in the art the means whereby the invention may be carried out, it will be understood that the invention may be embodied in still other forms without departing from the scope thereof as defined in the appended claims.

20 I claim:

1. In a device of the class described, a side frame, a bracket carried by said side frame, a lagged locking pin detachably and non-rotatively engaging said bracket, and a hanger journaled on said pin.

2. In a device of the class described, a relatively fixed member having an aperture therethrough, a pin non-rotatably mounted in said aperture, a relatively movable member journaled on said pin, and a lug projecting from said pin and acting normally to prevent withdrawal of said relatively movable member, said relatively movable member having a notch therein adapted to align with said lug to permit removal of said relatively movable member when the same is moved angularly to a position other than its normal position.

3. In a device of the class described, a relatively fixed member, a pin mounted in said member and having a lug projecting therefrom, a relatively movable member provided with an aperture to receive said pin and having a notch leading from said aperture, and another lug formed on said pin and adapted to prevent removal of said relatively movable member from said pin when said relatively movable member is in normal position, said notch being adapted to align with one of said lugs when said relatively movable member is moved from normal position to permit removal thereof from said pin.

4. In a brake hanger for railway cars, a bracket, a hanger, non-rotatively mounted means for connecting said bracket and said hanger, said means being arranged to permit detachment of said hanger when the latter is in some position other than the normal position, and means acting normally to prevent movement of said hanger to detaching position.

5. In a brake hanger for railway cars, a bracket, a hanger, and non-rotatively mounted means for connecting said bracket and

said hanger, said means being arranged to permit detachment of said hanger when the latter is in some position other than the normal position, said hanger being normally prevented from moving to detaching position by parts of the car structure.

6. In a brake hanger for railway cars, a side frame, a spring plank supported by said side frame, a bracket, a brake beam adapted to be supported between said spring plank and a wheel of the car, a hanger attached to said brake beam, and non-rotatively mounted means for connecting said hanger and said bracket, said connecting means being arranged to permit detachment of said hanger in one position thereof and positively to prevent such detachment in other positions thereof, said hanger being normally prevented from moving to detaching position by said brake beam, said spring plank and said car wheel.

7. In a device of the class described, a relatively fixed member and a relatively movable member having alining apertures, a pin adapted to engage said apertures for connecting said members, said members having notches communicating with said apertures and adapted to aline with each other when said members are in one relative position, and a plurality of lugs formed on said pin to prevent removal of said pin from either of said members when said members are in their normal relative positions.

8. In a device of the class described, a bracket having an aperture formed therethrough with a notch leading from said aperture, a pin mounted in said aperture and projecting from each end thereof, said pin having a lug adapted to seat in said notch, and a hanger having parts journaled on the projecting ends of said pin, said hanger having notches adapted to aline with the notch in said bracket when said hanger is moved from operative position to permit withdrawal of said pin from said bracket and said hanger, said pin having other lugs formed on the ends thereof to prevent removal of said hanger from said pin.

9. In a device of the class described, a side frame having side columns and an upper arch-bar, a bracket formed integrally with said side frame adjacent the junction of said arch-bar and one of said side columns, a brake hanger, means for detachably connecting said bracket and said hanger whereby the latter may be removed from said bracket when moved from normal operative position, and a brake beam connected to said hanger, said brake beam and said side frame being adapted normally to prevent movement of said hanger to a position wherein it may be detached from said bracket.

10. In a device of the class described, a bracket, a hanger, and a pin mounted in said bracket and having a lug projecting

therefrom, said hanger being provided with an aperture to receive said pin and having a notch leading from said aperture, said notch being adapted to register with said 5 lug when said hanger is in one position on said pin whereby said hanger may be removed, said pin being non-rotatively fixed with respect to said bracket.

11. In a brake hanger for a railway car, a 10 bracket, a pin non-rotatably mounted in said bracket, and a brake hanger journaled on said pin, said pin having a projecting lug acting normally to prevent withdrawal of said hanger, said hanger having a notch 15 adapted to register with said lug when said hanger is in inoperative position, whereby the latter may be withdrawn from said pin.

12. In a brake hanger for a railway car, a 20 bracket, a pin non-rotatably mounted in said bracket, and a brake hanger journaled on said pin, said pin having a projecting lug acting normally to prevent withdrawal of said hanger, said hanger having a notch 25 adapted to register with said lug when said hanger is in inoperative position, whereby the latter may be withdrawn from said pin, said hanger being normally prevented from moving to detaching position by parts of the car structure.

30 13. In a device of the class described, a bracket, a hanger and a pin for connecting

said bracket and said hanger, said bracket and said hanger having alining apertures adapted to be engaged by said pin and having notches communicating with said apertures, said notches being adapted to aline in one relative position of said hanger and said bracket, said pin having a lug adapted to engage said notches when the latter are in alinement, said lug being adapted to prevent withdrawal of said pin when said notches are out of alinement.

14. In a device of the class described, a bracket, a hanger, and a pin connecting said bracket and said hanger, said bracket and 45 said hanger having alining apertures adapted to be engaged by said pin and having notches communicating with said apertures, said notches being adapted to aline in one relative position of said hanger and said 50 bracket, said pin having a lug adapted to engage said notches when the latter are in alinement, said lug being adapted to seat in one of said notches when said notches are 55 out of alinement.

In testimony whereof, I have subscribed my name.
